UNITED STATES PATENT OFFICE

WALTER N. VANCE, OF CHICAGO HEIGHTS, ILLINOIS, ASSIGNOR, BY MESNE ASSIGNMENTS, TO LYON METAL PRODUCTS, INCORPORATED, OF AURORA, ILLINOIS, A CORPORATION OF ILLINOIS

LOCKER

Substitute for application Serial No. 344,586, filed December 13, 1919. This application filed August 12, 1922. Serial No. 581,487.

This invention relates in general to lockers, shelving and the like and has for a principal object the provision of a locker readily convertible from arrangement as a clothes or 5 wardrobe locker into a locker containing shelving and readily also adjustable into combinations of the two, i. e., arrangeable to provide space for the hanging of garments and shelves for receiving other articles. This application is for the subject matter of my 10 abandoned application 344,586 filed December 13, 1919.

A further object of the invention is the provision of a locker wherein the sides and back 15 i. e., all but the door frame, will be composed entirely of sheet metal and at the same time be strong and durable.

Another important object of the invention is the provision of new and improved adjustable shelving within lockers, said shelving 20 being of unusual strength, firmly held in position and easily moved from one height to another or removed entirely from the structure without disturbing other than the shelf 25 and the devices particularly associated with it.

Another important object of the invention is the provision of new and improved coat 25 hangers and coat hanger carriers, which will permit them to be taken out and positioned without moving the locker from position in use.

Other important objects of the invention 30 are the improvements in shelf construction and construction of shelf supports.

Numerous other objects and advantages of the invention will be apparent as it is better 35 understood from the following description, which, taken in connection with the accompanying drawings, discloses a preferred embodiment thereof.

Referring to the drawing,

Figure 1 is a front elevation of a locker 40 embodying my present invention;

Fig. 2 is a side view of the same;

Fig. 3 is a section taken substantially on the line 3—3 of Fig. 1;

Fig. 4 is a section taken substantially on the line 4—4 of Fig. 3;

Fig. 5 is a section taken similarly to Fig.

4 and showing the arrangement of a shelf with the front member and back joint closing member;

Fig. 6 is a section taken substantially on the line 6—6 of Fig. 5;

55

Fig. 7 is a detail enlarged front view of a shelf support;

Fig. 8 is a side view of the same showing parts to which it is attached in section;

Fig. 9 is a view similar to Fig. 8 showing 60 the shelf support in a position it assumes in being attached to said wall;

Fig. 10 is a partial perspective of an edge of the back wall;

Fig. 11 is a similar view of the angle member 65 provided to receive the front shelf supports;

Fig. 12 is a partial section showing the arrangement with the coat hanger carrier;

Fig. 13 is a section on the line 13—13 of 70 Fig. 12 and showing the assembly of a shelf with the garment hanger rod and also side wall garment hangers;

Fig. 14 is a section taken on the line 14—14 of Fig. 13;

75

Fig. 15 is a partial vertical section through the bottom of the structure showing a corner construction;

Fig. 16 is a perspective view of the reinforcing plate; and

80

Fig. 17 is a similar view of an end of one of the space closures.

For the purpose of illustrating my invention, I have shown on the drawing a locker provided with a door frame 21 of any usual or preferred construction and in which are hinged at 22 door closures 23. The locker includes side walls 24 and bottom wall 25 and a rear wall 26. Sides, rear and bottom walls are of sheet metal and, in the present instance, 90 the door frame, which, with the doors constitute the front wall, is composed of angle iron construction, having inwardly extending side flanges 27. The side walls extend from the floor to the top of the locker, are 95 of sheet metal and have their forward edges offset at 28 and disposed upon the inner face of the angle iron flange 27 at 29.

At the rear vertical edges, the material is bent at 31 to overlie the back wall, as may be 100

seen in Fig. 3 and in other figures. The back wall is also of sheet metal and extends between the side walls, having its edges offset at 32 from adjacent the edges of the flanges 33 of the side wall located at the back. Bolts 34 are secured through the overlying parts of the flanges 33 of the back wall 26 inwardly of the offsets 32, to secure the walls together at the back, and similar bolts 35 are disposed through the side wall edges 29 and the flange 27 of the door frame, to secure the side walls at the front. The bottom consists of a metal sheet turned down at its four edges at 36 into contact with the inner faces of the sides and back wall. A reinforcing plate, shown in perspective in Fig. 16, is provided at each rear corner. This consists of a metal sheet bent along its vertical center along lines of bend 37, to provide wings 38 disposed at right angles with each other and in contact with the inner faces of adjacent side and back walls. At the bottom, two inwardly extending mitred flanges are provided to stiffen the structure, and near the top, each wing is offset at 41 to provide upwardly extending flanges 42 for disposal within the flanges 36 of the bottom wall. Suitable apertures are provided to receive bolts 43, extending through the wings 42 and back 26, and side and back walls at the top, and similar bolts 44 extend through the reinforcing plate and adjacent walls at the bottom. The reinforcing plates reinforce the structure at the base and, in a measure, provide feet at the rear for it to rest upon. The inwardly spaced parts 45, at the edges of the back wall, stiffen the structure above the bottom and, by this construction, an extremely rigid locker may be provided of relatively light material.

The spaced parts 45 of the back wall are provided at intervals with perforations 46 throughout its length, (Fig. 10) and an angle member 47, preferably of sheet material and having one part 48 provided with similar perforations 49, is arranged adjacent the front of the locker and at each side. The other flange 51 of this angle is bolted into place by the bolts 35, already mentioned as holding the side walls to the door frame. Two vertical perforated uprights, or strips, are thus provided within the locker at each side, the perforations being arranged in registration and extending through the strips in a front-to-back direction. From certain aspects of the invention, these strips may be considered a part of the walls.

The perforations in the strips are adapted to be engaged by supports, upon which may rest, or with which may be engaged shelves, garment hangers, and the like. These supports are preferably constructed, as is possibly best shown in Figs. 7 to 9, of a metal strap 52, having an end or arm 53 at its top, which is offset slightly at 54 and provided with upper and lower shoulders 55 and 56.

The width of this arm 53 is appropriate to permit it to pass through the perforations 46 or 49 and it is provided with a head 57, slightly larger than its neck 58 and still adapted to pass through the perforations 46 and 49. The length of the body of the support is slightly greater than the distance between two successive perforations 46 and 49, and at, or near the bottom, a boss or lug 59 is stamped, or pressed from the support and enters into the perforation next below that in which the upper arm 53 is engaged. The support has an outwardly extending arm or part 60 at its bottom, upon which the shelf, or garment hanger carrier may rest.

The method of inserting the supports is illustrated in Figs. 8 and 9, and an inspection of these figures will render description of this operation unnecessary. The shelves may consist of metal sheets 61 bent downwardly at the side edges at 62 to provide downwardly extending flanges 63 and these flanges are bent inwardly again at 64 at the bottom to provide inwardly extending parts 65, which terminate in an upwardly bent portion or flange 66. At the edges 62 and 64, the metal is distorted to reinforce the shelf structure and this is accomplished by pressing in small gussets 67, which act as cross braces. These depressions, or gussets 67, are made at relatively frequent intervals, as may be seen by viewing Fig. 3. In the shelves that are to carry the heavier loads, bars 68 are inserted within the channel-shaped flanges at the sides of the shelves, as in Fig. 5, these bars preferably fitting tightly in place and occupying the space between the flanges 66 and the depressions 67 at the bottom and resting against the depressions 67 at the top.

It will be noted that the shelf supports extend down between the adjacent edges of the shelf and the back wall and I provide means for covering such space as will now be described. A sheet of metal 69 is bent at right angles at its edges at 71 and bent back on itself to form a channel 72. The height of this arrangement is preferably such that its top comes adjacent a perforation 46 at each end and the metal is cut and bent up at 73 to provide lips insertible in the presented perforations to hold the upper part of the space covering member in position. These space covering members are assembled in the structure by inserting the lips 73 through the appropriate perforations, while the space covering members are in inclined position and then swinging them down about the hinged connection into the position shown in Fig. 5. The return flanges 72 of the space covering members are cut away, as indicated at 74, to permit them to accommodate the offset vertical parts 45 of the back wall and, of course, the lip 73 is located in the upper cut-away part 74.

Shelf fronts may be readily provided and

be of similar construction, being shown, in the present instance, as consisting of metal sheets 75 having return flanges 76 like the return flanges 72 of the back walls, and similarly cut away at the ends to accommodate the perforated part 28 of the front angles. These shelf fronts may be secured in position by bolts 77 passing through them and through appropriate perforations 49, or any other fashion as may be desired. The shelf assembly, of course, may vary within wide limits, but is shown on the drawing in Figs. 1 and 2 as having a shelf 81 at the top and clothes hanger support carrier 82 with clothes hanger supports immediately therebeneath and with a shelf 83 at the bottom. Of course, other shelves may be readily inserted and the locker may, if desired, be entirely occupied by shelves, or have merely clothes hangers therein. The shelf at the top is preferably provided with a clothes hanger rod and to this end is provided with end flanges 86 (Fig. 14), and between which is supported a tube 86 provided with wooden plugs 87 in its ends, 25 into which plugs extend nails, or other fastening devices 88 disposed through the end flanges 85.

The clothes hanger support carrier preferably consists of a metal sheet, bent to the general form of the space closers and shelf front and of a length sufficient to permit them to be disposed about the sides and back of the locker. Each carrier is provided with the return flanges 89 extending out from the body 30 of the strip 91, which flanges are cut through at the corners to permit bending of the body sheet to the right angle form shown. Clothes hangers 92, of any suitable or preferred form, are secured by bolts 93 in this strip. At 35 the back, the clothes hanger carrier rests upon shelf supports 52 and at the front is supported by shelf supports which are inserted into the ends of the upper return bent flanges 89. The carrier is positioned by first engaging 40 with the front shelf supports when in upwardly and rearwardly inclined position and then is moved down to rest upon the shelf supports at the rear. That is to say, the front shelf supports are first inserted in the upper return bends and these front shelf supports are then positioned in the appropriate perforations 49 at the front and the whole is moved down to the assembly position.

It is thought that the invention and many 45 of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof. *

I claim:

65 1. A sheet metal locker, comprising, body

walls providing an enclosing casing for the locker, two of said adjacent wall portions being arranged in overlapping formation at a corner of the casing, the inner of said overlapping wall portions having an integral interior projection bent substantially at right angles and provided with an extended flange 70 projecting substantially parallel with the main wall portion and abutting the inner face of an exterior wall to provide spaced apart wall portions, said flange having a series of perforations adapted adjustably to receive supporting members. 75

2. A sheet metal locker, comprising sheet metal walls connected together at adjacent ends and suitably bent to form a corner for the locker, a bottom member for the locker having downturned flanges at its sides and end secured to said walls adjacent the base thereof, and a reinforcing basal support in the locker, comprising a sheet metal member bent to provide angularly disposed plates, and means for connecting said plates to the adjacent vertical walls at their bases for providing a rigid support for the locker, the upper portion of said reinforcing member being secured to the downturned flanges of 80 said bottom member. 85

3. A locker, comprising sheet metal walls having overlapping edges secured together 90 adjacent the corner, one of said edges being continued beyond the point of attachment parallel to and spaced away from the other, and provided with a series of vertical perforations spaced apart and shelf supports, each comprising a main supporting member and a substantially flat shank disposed at substantially right angles thereto, said shank having an inwardly extending lug adjacent the bend, said shank having at its outer end a tip bent laterally out of the plane of the shank and provided with a narrowed end adapted to pass through a perforation, said narrowed end and inwardly extending lug at the bend of the shank being spaced sufficiently apart, so that 95 when the narrowed end is inserted in one of the perforations the inwardly extending lug will pass into the next adjacent perforation with the shank lying flat against the wall portion. 100 105

4. A locker, comprising sheet metal walls, providing a vertical series of spaced perforations, a supporting member, comprising a shank having a substantially arcuate cross-section, said shank having an integral flat wall extending therefrom at right angles, that portion of the flat wall at its juncture with the shank having an outwardly extending wedge shaped lug, the upper portion of the flat member having shoulders inclined inwardly and terminating in a narrow end, said end and outwardly extending lug being spaced apart a sufficient distance so that when said end is inserted in a perforation of the wall, the laterally extending lug will rest in 110 115 120 125 130

an adjacent perforation with the flat portion lying flatly against the wall member.

5. A locker, comprising body walls, one of which walls has an extreme end bent at right angles and adapted to overlie the extreme edge of an adjacent wall to form a corner, the extreme edge of the inner wall of the overlapping walls being bent inwardly and spaced away from the overlapping wall and extending in such spaced relation beyond the point of connection in said overlapping walls to provide a space between said extension and one of said overlapping walls, said extension having a vertical tier of spaced apart notches, 10 the other end of said wall, which has the angularly bent flange, having an angle iron connected thereto at its end, said connection including a substantially L-shaped member, the flange of which lies parallel to the integral, perforated extension of the above mentioned wall member and spaced substantially the width of the locker therefrom, said portion of the L-shaped member having a like vertical tier of spaced apart perforations registering with those of the integral extension and a series of bracket members adapted to be positioned in said perforations and to form supports for the lockers.

6. A locker, comprising vertically arranged 20 perforated members, shelf supports individualized to shelves carried thereby and engaging said perforations, shelves carried by said shelf supports, and means closing the space between said shelf and said walls and also 25 engaged in said perforations for securing said shelf in position.

7. Metal shelving, comprising vertically extending perforated members arranged in rectangular relation, shelf supports each having an end extending up above the shelf and arrangeable through a perforation, and an end extending out for arrangement beneath the shelf whereby to support the shelf from suspended supports.
